UNITED STATES PATENT OFFICE.

LEO GUDEMAN, OF NEW YORK, N. Y.

DESIGN FOR AN ARTICLE OF TABLE ORNAMENTATION ADAPTED FOR USE AS A VASE.

48,275.

Specification for Design.

Patented Dec. 14, 1915.

Application filed July 12, 1915. Serial No. 39,487. Term of patent 3½ years.

To all whom it may concern:

Be it known that I, LEO GUDEMAN, a citizen of the United States, residing at New York city, in the county and State of New York, have invented a new and ornamental Design for an Article of Table Ornamentation Adapted for Use as a Vase, of which the following is a specification, reference being had to the accompanying drawing, forming part thereof.

The figure is a perspective view of an article of table ornamentation, showing my new design.

I claim:—

The ornamental design for an article of table ornamentation adapted for use as a vase.

LEO GUDEMAN.

Witnesses:

CLARICE FRANCK,
JUDITH PARDEE.
